UNITED STATES PATENT OFFICE

119,527

DESIGN FOR A ROAD LAMP FOR AUTOMOTIVE VEHICLES

Oliver C. Ritz-Woller, Chicago, Ill.

Application January 30, 1939, Serial No. 82,656

Term of patent 7 years

To all whom it may concern:

Be it known that I, Oliver C. Ritz-Woller, a citizen of the United States, residing at Chicago, in the county of Cook and State of Illinois, have invented a new, original, and ornamental Design for a Road Lamp for Automotive Vehicles, of which the following is a specification, reference being had to the accompanying drawing, forming part thereof.

In the drawing—

Fig. 1 is a side elevational view of a road lamp for automotive vehicles embodying my new design;

Figs. 2 and 3 are front and rear elevational views, respectively, of the lamp with the bracket member broken away for convenience of illustration.

The dominant features of the design reside in the solid line showing of the configurations of the lamp, front rim and lens, combined substantially in the manner shown.

I claim:

The ornamental design for a road lamp for automotive vehicles, substantially as shown and described.

OLIVER C. RITZ-WOLLER.
